DESIGN FOR A FOLDING PICTURE FRAME OR SIMILAR ARTICLE

Ralph Kraus, New York, N. Y.

Application December 22, 1945, Serial No. 124,984

Term of patent 14 years

(Cl. D29—20)

To all whom it may concern:

Be it known that I, Ralph Kraus, a citizen of the United States of America, residing in New York city, county of New York, and State of New York, have invented a new, original, and ornamental Design for a Folding Picture Frame or Similar Article, of which the following is a specification, reference being had to the accompanying drawings, forming part thereof, wherein,

Figure 1 is a front elevational view of a folding picture frame or similar article showing my new design in folded position.

Figure 2 is a side elevational view.

Figure 3 is a rear elevational view.

Figure 4 is a top plan view.

Figure 5 is a view similar to Figure 1, showing the frame in open position.

I claim:

The ornamental design for a folding picture frame or similar article, substantially as shown.

RALPH KRAUS.
